(57) **CLAIM**

The ornamental design for a hanging light as shown and described.

DESCRIPTION

FIG. 1 is a perspective view of a hanging light showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines shown in the figures are for the purpose of illustrating portions of the hanging light that forms no part of the claimed design.
